FAIR LEAD FOR EXCAVATORS

Mitchell L. Fykse, South Milwaukee, Wis., assignor to Bucyrus-Erie Company, South Milwaukee, Wis., a corporation of Delaware

Application September 2, 1932. Serial No. 631,478

10 Claims. (Cl. 254—190)

My invention relates to new and useful improvements in fairleads for excavators, and has particular application to the means for guiding the drag-rope upon the winding drum.

5 In excavators of this general character, it is impossible for the bucket to be at all times in such a position with respect to the drag-rope winding drum, as to permit of a straight pull at right angles to the axes of said drum. It is therefore essential that means be provided for correcting the angular displacement of the drag-rope before it is wound on the drum. Accordingly it is one object of my invention to provide a simply constructed fairlead, which will guide a 15 drag-rope both vertically and horizontally, so that the rope, as it winds upon the drum, shall at all times be quite approximately perpendicular to the axes of the drum.

It also frequently becomes very desirable to 20 change the front end equipment of a dragline excavator, as, for instance, to substitute a longer boom and a smaller bucket, or to convert the dragline excavator into a drag shovel, by substituting a different boom, with a handle carrying 25 a dipper. In such cases, the change in the amount of drag-rope pull required will make a different speed of operation more economical. This different speed is obtained by changing the lagging of the drag-rope drum, thereby changing 30 its diameter. Such a change in the diameter of the drum will, however, change the direction of that portion of the drag-rope which is between the drum and the deflecting sheaves. In fairleads as heretofore constructed, the angle between 35 the plane of the deflecting sheaves and the horizontal plane is fixed and unalterable; so that the rope reaches the deflecting sheaves in the correct direction only when the size drum is used for which the particular fairlead has been designed. If the diameter of the drum is changed, either by substitution or by lagging, then when 40 the rope is payed out from the drum, there will be a tendency of the rope to run off the deflecting sheave, which will cause quite excessive frictional 45 wear of the rope against the sides of the rope groove on the sheave. There will be a similar excessive friction when the rope is being wound upon the drum.

50 A further object of my invention is to provide a fairlead that is adjustable to eliminate completely this tendency of the rope to run off the deflecting sheaves, and the consequent rope wear. This I accomplish by providing a fairlead which 55 is adjustable to bring the deflecting sheaves into

correct position to receive and deliver the rope, for any desired drum diameter.

In addition to these stated objects, I have worked out a number of novel and useful details, which will be readily evident as the description 60 progresses.

My invention consists in the novel parts, and in the combinations and arrangements thereof, which are defined in the appended claims; and of which one embodiment is exemplified in the 65 accompanying drawing, which is hereinafter particularly described and explained.

Throughout the description, the same reference number is applied to the same member or to similar members.

Referring to the drawing, it will be seen that: Figure 1 is a side elevation of my fairlead, as attached to the front end of a dragline excavator.

Figure 2 is a front elevation, as indicated in Figure 1, by the line 2—2.

Figure 3 is a plan view, partly in section, as taken along the line 3—3 of Figure 1.

In the embodiment of the invention shown in the drawing, the vertical guiding sheaves 11, 12, are journaled in a one piece frame 13. This frame includes a pair of side plates 14, 15, which are vertically disposed and horizontally spaced. These side plates are connected together at their back edges, as at 16, and said connected portion merges into vertically spaced arms having pivot 80 ears, 17, 18, formed on their ends.

These ears are adapted to straddle the attaching portion of an excavator base frame 19, which attaching portion also consists of a pair of vertically spaced pivot ears, 20, 21. The ears 17, 18 have their openings vertically aligned with the corresponding openings in pivot ears 20, 21, and a pivot pin, 22, is inserted through the four aligned openings. This pin is prevented from motion with respect to pivot ears 20, 21, by pins 90 23, 24, thereby ensuring that wear shall rather be taken by pivot ears 17, 18, than by pivot ears 20, 21, as the former are more easily repaired. Washers are placed between pivot ears 17 and 20 and between pivot ears 18 and 21. Thus the 100 fairlead may readily swing horizontally.

The vertical sheaves 11, 12, which are journaled between the side plates 14, 15, have their axes 25, 26, vertically spaced and parallel, axis 26 of the lower sheave being horizontally nearer 105 the pivot pin 22, than the axis 25.

The inner faces of the side plates 14, 15, are reinforced with various stiffening flanges, as shown dotted in Figure 1. For additional strength, corresponding flanges may bridge 110

across from one side plate to the other, at such places as do not interfere with the placing of sheaves 11, 12 or with the passage of the rope, 27.

At the forward end of each of the side plates 5 14, 15, there are projections 28, which serve as supports for a pair of rope guides, 29, whose function is to ensure the allowing of rope 27, in the plane of the sheaves 11, 12. When the bucket (not shown) is off to one side of the direction to which 10 the fairlead is oriented, the forward portion of rope 27 will bear against one of the rope guides 29, thereby swinging the fairlead about pivot pin 22, to the correct position. These rope guides 29 are secured to the rope guide support 28, by bolts 15 30, and are rigidly held spaced apart the proper distance by spacers 31, which are held between the rope guides 29 and secured by bolts 32.

Exactly midway between axes 25 and 26 of the 20 upper and lower guide sheaves 11 and 12, the side plates 14, 15, carry hubs 33, 34, through which pass aligned pins 35, 36, which serve as pivots for a unitary deflecting sheave yoke, 37. The 25 yoke 37 carries, rotatably mounted, two substantially horizontal deflecting sheaves 38, 39, of equal diameter, these sheaves being pivoted on parallel pins 40, 41, respectively.

Pivot pins 40 and 41 are so positioned in yoke 37, that the central plane of deflecting sheaves 38, 39 passes through the axes of yoke pivot pins 35, and 36, and so that the central plane of the 30 two guide sheaves 11, 12 passes parallel to, and midway between pins 40 and 41.

The upper pivot ear 17 of the fairlead frame 35 13 has a rearward horizontal projection, 42, to which is removably fastened, as by bolts, one of which is shown at 43, a yoke support, 44, the upper portion of which is removably fastened, as by bolts 45, to the under side of yoke 37. The yoke support, 43, is of such height that the rope 40 27, may pass from between sheaves 38 and 39 to the winding drum, (not shown,) without having any upward or downward bend adjacent the sheaves 38, 39. The rope 27 has thus no tendency 45 to climb out of the groove of sheave 38 or sheave 39 and is not subjected to excessive wear.

Furthermore, pins 40 and 41 are so positioned in yoke 37, that the point midway between the centers of sheaves 38 and 39 shall be directly on the prolongation of the axis of fairlead pivot pin 22. Therefore any swinging of the fairlead about pin 22 will not cause any material departure from the correct conditions stated above.

When it becomes advisable, for any reason, to 55 change the diameter of the drum upon which the drag rope 27 is wound, as by different drum lagging, a different yoke support, of the height required by the new conditions, may easily and quickly be inserted in place of yoke support 44, or only one yoke support may be provided, the different heights being obtained by inserting a 60 filler or fillers, (not shown) between yoke support 44 and the projection 42 upon which it is bolted. For the range of drum sizes at all likely to be required, it is quite obvious that the displacement 65 of the point midway between the centers of sheaves 38 and 39 from the prolongation of the axis of pin 22 will be in any case so slight as to be quite negligible.

Having now described one form of my invention, it is obvious that I have provided a fairlead that will in all cases deliver the drag rope in correct relation to the drag drum, and is capable of compensating for any necessary change in the diameter of the drum.

75 I therefore claim:

1. A guide structure, comprising: a frame, pivoted for rotation about an axis; a pair of coplanar sheaves, carried by said frame and disposed for rotation in a plane passing through said axis; a pivot, carried by said frame; a member, disposed for rotation about said pivot; a pair of coplanar sheaves carried by said member, and disposed for rotation in a plane passing through said pivot; and an auxiliary support for said member. 80

2. A guide structure, comprising: a frame, pivoted for rotation about an axis; a pair of coplanar sheaves, carried by said frame and disposed for rotation in a plane passing through said axis; a pivot, carried by said frame; a member, disposed for rotation about said pivot; a pair of coplanar sheaves carried by said member, and disposed for rotation in a plane passing through said pivot, the second pair of sheaves being so positioned that the point midway between their centers lies substantially upon the prolongation of said first named axis; and an auxiliary support for said member. 90

3. A guide structure, comprising: a frame, pivoted for rotation about an axis; a pair of coplanar sheaves, carried by said frame and disposed for rotation in a plane passing through said axis; a pivot, carried by said frame; a member, disposed for rotation about said pivot; and a pair of coplanar sheaves, whose plane of rotation is perpendicular to that of the first named pair of sheaves. 100

4. A guide structure, comprising: a frame, pivoted for rotation about an axis; a pair of coplanar sheaves, carried by said frame and disposed for rotation in a plane passing through said axis; a pivot, carried by said frame; a member, disposed for rotation about said pivot; a pair of coplanar sheaves carried by said member, whose plane of rotation is perpendicular to that of the first named pair of sheaves; and an auxiliary support for said member. 110

5. A guide structure, comprising: a frame, pivoted for rotation about an axis; a pair of mutually tangent sheaves, carried by said frame; a pivot, carried by said frame, and positioned at the point of common tangency of said sheaves; a member carried by, and rotatable about, said pivot; and a pair of mutually tangent sheaves carried by said member, and disposed for rotation in a plane passing through said pivot. 120

6. A guide structure, comprising: a frame, pivoted for rotation about an axis; a pair of mutually tangent sheaves, carried by said frame; a pivot, carried by said frame, and positioned at the point of common tangency of said sheaves; a member carried by, and rotatable about, said pivot; a pair of mutually tangent sheaves carried by said member, and disposed for rotation in a plane passing through said pivot; and an auxiliary support for said member. 130

7. A guide structure, comprising: a frame, pivoted for rotation about an axis; a pair of coplanar sheaves carried by said frame; a pivot, carried by said frame; a member disposed for rotation about said pivot; and a pair of sheaves carried by said member, the plane of rotation of said second pair of sheaves being perpendicular to the plane of rotation of the first pair. 140

8. A guide structure, comprising: a frame, pivoted for rotation about an axis; a pair of coplanar sheaves carried by said frame; a pivot, carried by said frame; a member disposed for rotation about said pivot; a pair of sheaves carried by said member, the plane of rotation of said 150

second pair of sheaves being perpendicular to the plane of rotation of the first pair; and an auxiliary support for said member.

9. A guide structure comprising: an axis, a pair of rigidly spaced parallel plates rotatable about that axis; a pair of mutually tangent sheaves carried by said plates; a pivot, carried by said plates; a member disposed for rotation about said pivot; and a pair of mutually tangent sheaves, carried by said member, and so positioned that their point of common tangency lies substantially upon the prolongation of said first named axis; and an auxiliary support for said member.

10. A guide structure comprising: an axis, a pair of rigidly spaced parallel plates rotatable about that axis; a pair of mutually tangent sheaves carried by said plates; a pivot, carried by said plates; a member disposed for rotation about said pivot; a pair of mutually tangent sheaves, carried by said member, and so positioned that their point of common tangency lies substantially upon the prolongation of said first named axis; and an auxiliary support for said member. 80
